[57] CLAIM

The ornamental design for a container for a resuscitation mask, as shown and described.

DESCRIPTION

FIG. 1 is a perspective view of a container for a resuscitation mask showing my new design;

FIG. 2 is a front elevational view thereof;

FIG. 3 is a right side elevational view thereof, the left side being a mirror image of that shown;

FIG. 4 is a rear elevational view thereof;

FIG. 5 is a top plan view thereof;

FIG. 6 is a bottom plan view thereof; and

FIG. 7 is a perspective view thereof, showing the container in an open position. The broken-line disclosure of the resuscitation mask in FIGS. 1 and 7 is for illustrative purposes only and forms no part of the claimed design.
